UNITED STATES PATENT OFFICE.

GEORGE WASHINGTON OLIVER, OF CHICAGO, ILLINOIS.

ASH-TRAY HOLDER.

Application filed March 19, 1928. Serial No. 262,923.

This invention relates to an improved ash tray holder and more particularly to an improved spring clamp mounting whereby an ash tray or the like may be conveniently mounted in a horizontal position upon a vertical post or upright.

It is an object of this invention to provide an improved ash tray and holder therefor adapted to be conveniently clamped upon a vertical upright and having means for holding and bracing an ash tray or similar receptacle in a substantially horizontal position.

It is also an object of this invention to provide an ash tray receptacle or the like with a supporting bracket having secured thereto a spring clamp mechanism adapted to be applied to supporting posts of different diameters.

It is an important object of this invention to provide an improved supporting means for an ash tray or similar receptacle, said supporting means embracing a spring clamp having a slotted latch member pivotally engaged on the spring clamp and adapted to be positioned to permit a corrugated arm of the clamp to be adjustably engaged therethrough to hold the clamp tightly engaged around an upright support against which the lower end of the supporting bracket is adapted to engage to brace and hold the receptacle in a substantially horizontal position at all times.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of an improved ash tray and holder embodying the principles of this invention shown clamped in position upon an upright support and indicating the operation of the clamp members in dotted lines.

Figure 2 is a vertical sectional view taken on line II—II of Figure 1.

Figure 3 is a detail transverse section taken on line III—III of Figure 2.

Figure 4 is an enlarged vertical view of

the end of the clamp mechanism taken on line IV—IV of Figure 2.

As shown on the drawings:

The reference numeral 1 indicates an upright post forming a part of a bed, a table, or any other article upon which it may be desired to clamp an improved ash tray of the type hereinafter described. The improved ash tray and holder comprises a clamp member consisting of arms 2 and 3 integrally connected by a bight portion 4 to form a spring connection for the clamp arms. The arms 2 and 3 are shaped to afford outwardly curved sections to permit the same to clamp against the post 1 as illustrated in Figure 1. Hinged or pivotally mounted at 5 on the outer end of the resilient clamping arm 2 is a latch plate or draw buckle 6 having a group of parallel slots 7 formed transversely therein as clearly illustrated in Figure 4.

The latch plate or draw buckle 6 is adapted to be swung from the dotted line position of Figure 1 into the full line position of said figure to permit the grooved or corrugated end 8 of the resilient clamp arm 3 to be engaged through one of the latch slots 7 thereby resiliently holding the clamp tightly against the surface of the upright 1. The pivoted latch plate or draw buckle may be engaged in any one of the corrugations of the latching end 8 of the clamp arm 3 to draw the clamp arms together to properly hold the ash tray in a predetermined position. In order to prevent the clamping member or bracket from having sliding movement on the support or post 1 the inner faces of the clamp arms 2 and 3 may be lined with felt or other suitable materials to obviate slippage.

The bight portion 4 of the clamping bracket is riveted or otherwise rigidly secured at its middle portion to one face of the upper end of a plate or bar 9 on the opposite face of which an ash tray or other receptacle 10 is rigidly secured at right angles. Supported on the flange 11 of the ash tray 10 adjacent the upright bar 9 is a match box holder 12. The ash tray 10 is braced in position by means of a brace bar 13, one end of which is rigidly secured to the undersurface of the ash tray 10 while

the other end is rigidly secured to the lower portion of the plate or bar 9. Rigidly secured on the rear face of the lower end of the plate or bar 9 is a spring foot or spacer member 14, the inner faces of the spring arms of which may be lined with felt or other suitable materials if desired to prevent slippage of the bracket on the upright support 1. The spring foot 14 is adapted to seat against the upright or post 1 as illustrated in Figure 2 to hold the bar 9 in a substantially upright position parallel to the supporting post 1 so that the ash tray is braced in a substantially horizontal position in a convenient position for use.

It will be noted that the improved ash tray and the supporting clamp therefor may be readily engaged on a bed post, upon the leg of a table, or upon any suitable piece of furniture or on a wall support to hold the ash tray or receptacle in a convenient position for use. The improved supporting clamp forming a part of the ash tray supporting mechanism may be conveniently engaged upon an upright support and by means of the draw buckle or apertured latch plate, the arms of the clamping device may be drawn together to securely clamp the ash tray holder in place. By providing the draw buckle or latch plate 6 with a plurality of parallel slots 7 the corrugated spring end 8 of the clamping arm 3 may be engaged in any one of said slots depending upon the thickness or the diameter of the upright supporting member upon which the clamping device is to be engaged.

It will of course be understood that many changes may be made and numerous details of construction may be varied through a wide range without departing from the principles of this invention, and it is therefore not purposed limiting the patent granted hereon, otherwise than necessitated by the scope of the appended claims.

I claim as my invention:

1. An ash tray device comprising a connecting bar, a spring clamp rigidly secured on one end thereof adapted to be engaged on a support, a spring foot engaged on the other end of said bar adapted to seat against the support to hold the bar in spaced par-

lel relation with the support, receiver means rigidly secured to said bar opposite said spring clamp, and a brace member connected to said receiver means and to the lower end of said bar to brace the receiver means in place.

2. An ash tray holder device comprising a bar, an ash tray rigidly secured thereon, a brace member secured to said tray and to said bar to hold the tray braced in position, a spring foot secured to said bar adapted to rest against a support, a spring clamp rigidly secured to said bar adapted to be engaged on opposite sides of the support, and a slotted draw buckle pivoted on said spring clamp to clamp the same on said support to hold the tray in a predetermined position.

3. In a device of the class described the combination with a bar, of a receptacle secured thereto, a brace member connecting said receptacle to said bar to brace the receptacle in position with respect to said bar, a resilient foot on said bar adapted to seat against a supporting member to hold the bar in parallel relation thereto, spring clamping arms connected to said bar adapted to be engaged on opposite sides of the support, a slotted latch member hingedly connected to one of said arms, and a corrugated extension integrally formed on the other of said arms adapted to be engaged through one of the slots of said latch member to hold the resilient arms tightly clamped against the supporting member to hold the entire device properly positioned for use.

4. The combination with a receptacle and a supporting bracket therefor, of a spring foot on one end of said bracket, and a clamping member on the other end of said bracket comprising a pair of spring arms, a bight portion integrally connecting said spring arms to said bracket, a slotted plate hingedly connected on one of said arms, and a corrugated extension on the other of said arms for coaction with said hinged slotted plate to permit the spring arms to be removably clamped on a support to hold the receptacle in place.

GEO. W. OLIVER.
